UNITED STATES PATENT OFFICE

123,894

DESIGN FOR A GAS RANGE

Elmer D. Pellegrin, Woodstock, Ill., assignor to
Geo. D. Roper Corporation, Rockford, Ill., a corporation of Illinois

Application March 16, 1940, Serial No. 90,979

Term of patent 7 years

To all whom it may concern:

Be it known that I, Elmer D. Pellegrin, a citizen of the United States, residing at Woodstock, in the county of McHenry and State of Illinois, have invented a new, original, and ornamental Design for a Gas Range, of which the following is a specification, reference being had to the accompanying drawing, forming part thereof.

In the drawing:

Fig. 1 is a perspective view of a gas range showing my new design;

Fig. 2 is an enlarged front elevational view of

the combined flue deflector, timer, condiment shakers, and support for the same, shown in full lines in Fig. 1;

Fig. 3 is a top plan view of Fig. 2, and

Figs. 4 and 5 are end elevational views thereof, taken from opposite ends.

The dominant features of the design are those shown in full lines.

I claim:

The ornamental design for a gas range, substantially as shown and described.

ELMER D. PELLEGRIN.
